US0D1019945S

(12) **United States Design Patent** (10) **Patent No.:** **US D1,019,945 S**
(45) **Date of Patent:** **** Mar. 26, 2024**

(54) **SUTURE ANCHOR INSERTION DEVICE**

(71) Applicant: **Medos International Sàrl**, Le Locle (CH)

(72) Inventors: **Jordan N. Jacobs**, Randolph, MA (US); **Ravi Patel**, East Providence, RI (US); **Mark Shainwald**, Raynham, MA (US)

(73) Assignee: **Medos International Sarl**, Le Locle (CH)

(**) Term: **15 Years**

(21) Appl. No.: **29/821,482**

(22) Filed: **Dec. 30, 2021**

(51) LOC (14) Cl. **24-02**

(52) U.S. Cl.

USPC **D24/145**

(58) **Field of Classification Search**

(57) **CLAIM**

The ornamental design for a suture anchor insertion device, as shown and described.

DESCRIPTION

FIG. 1 is a perspective view of a new design of a suture anchor insertion device;

FIG. 2 is a front view of the device of FIG. 1;

FIG. 3 is a back view of the device of FIG. 1;

FIG. 4 is a left view of the device of FIG. 1;

FIG. 5 is a right view of the device of FIG. 1;

FIG. 6 is a top view of the device of FIG. 1; and,

FIG. 7 is a bottom view of the device of FIG. 1.

The broken lines in the drawings form no part of the claimed design.

1 Claim, 5 Drawing Sheets
